UNITED STATES PATENT OFFICE.

SAMUEL H. LIMBERT, OF SPRINGFIELD, OHIO, ASSIGNOR OF ONE-HALF TO CHARLES E. BRENING, OF SPRINGFIELD, OHIO.

BOILER-FLUE CLEANER.

No. 913,963.

Specification of Letters Patent. Patented March 2, 1909.

Application filed September 3, 1908. Serial No. 451,467.

To all whom it may concern:

Be it known that I, SAMUEL H. LIMBERT, a citizen of the United States, residing at Springfield, in the county of Clark and State of Ohio, have invented certain new and useful Improvements in Boiler-Flue Cleaners, of which the following is a specification, reference being had therein to the accompanying drawings.

10 My invention relates to boiler flue cleaners, and more particularly to that type of flue cleaner employing a jet of steam which is discharged into the flue.

The object of the invention is to provide a 15 cleaner of this character which will be so mounted relatively to the boiler flues that it can be moved into position to discharge into any of said flues and can be adjusted toward and away from the flues; which will be 20 provided with means for preventing the burning of that portion of the same lying within the furnace walls; which will be provided with means for rotating the same; which will be provided with means for drawing 25 off the waters of condensation and preventing their discharge into the flues; and further, to provide such a device which will be simple and comparatively inexpensive in construction, but will be possessed of a high 30 degree of efficiency.

With these objects in view my invention consists in certain novel features and in certain parts and combinations to be herein-after described, and then more particularly 35 pointed out in the claims.

In the accompanying drawing is a vertical sectional view through one end of a boiler furnace and a boiler, showing my invention applied thereto.

40 In this drawing I have illustrated the preferred form of my invention and have shown the same as comprising a spray pipe 1 rotatably and slidably mounted in the rear wall 2 of a boiler furnace and preferably journaled 45 in boxes 3 mounted in the opposite ends of the bearing aperture in the wall 2. The inner end of the pipe 1 extends at substantially right angles thereto and transversely to the boiler to form a spray head or discharge nozzle 4. This discharge nozzle has its end closed, as shown at 6, and is provided in the side adjacent to the boiler with a series of apertures 5 which are so arranged therein that, as the discharge nozzle is moved across 50 the end of the boiler, one or more of these 55 apertures will be brought into alinement with each of the flues. The spray pipe 1 is preferably journaled in the wall 2 in a position substantially midway between the opposite sides of the boiler and with its longitudinal axis in substantially the same horizontal plane with the upper wall of the uppermost of the flues in said boiler. Thus, by moving the pipe 1 through an arc of 180 degrees, the discharge nozzle will be moved 60 across all that portion of the boiler in which the flues are mounted and some one or more of the apertures 5 will have been brought into alinement with each of the flues. I have 65 here shown the apertures 5 as so arranged in the discharge nozzle that one aperture is in alinement with each flue, but it will be obvious that any suitable number and arrangement of apertures may be employed. Suitable means, such as an adjustable collar 7, 70 are provided for limiting the inward movement of the pipe 1 so that the discharge nozzle 75 may be supported in the desired relation to the boiler flues.

Steain is preferably supplied to the spray 80 pipe 1 by means of a supply pipe 8, which, as here shown, is of an exterior diameter slightly less than the interior diameter of the spray pipe 1 and has its adjacent end inserted in the outer end of that pipe. The 85 spray pipe 1 is provided with a suitable stuffing box 9 to close the joint between the same and the supply pipe 8 and enable the spray pipe to be moved longitudinally of the supply pipe. The supply pipe is provided 90 with suitable controlling means, such as a valve 10, and has, at a point beyond and adjacent to this valve, a suitable drain cock, by means of which the water of condensation 95 accumulating above the valve 10 may be drawn off, thus avoiding the discharge of the same into the flues when the valve 10 is first opened. In the present instance, the controlling valve 10 is shown in the form of a globe valve and that portion of the valve 100 casing opposite the controlling handle is provided with a reinforced portion 11 having an outlet aperture 12 which is controlled by a valve 13, of any suitable character. The supply pipe 8 is also provided, at a point between the controlling valve 10 and the spray pipe 1, with a check valve adapted to be held in its closed position by the passage of steam through the supply pipe 8, and to automatically open, when the steam has 105 110

been cut off from that pipe, to admit air to the pipe and to discharge nozzle 4, the passage of air through the discharge nozzle being sufficient to effectually prevent the burning 5 of that nozzle and that portion of the pipe 1 which lies within the furnace walls. And further, the passage of the air through the discharge nozzle 4 serves to facilitate the draft through the furnace. In the present 10 instance, this check valve is shown as consisting of a valve casing 14 connected to the supply pipe 8 by means of a T-joint 15 and having its upper end provided with an inlet 16 controlled by a valve 17 having a stem 18 guided in a spider 19 arranged within the casing 14. When the valve 10 is open and the steam is passing through the supply pipe, a sufficient amount of steam will pass into the casing 14 to force the valve 17 against its 15 seat and hold the same in its closed position. 20 As soon as the valve 10 has been closed, however, to cut off the steam from the supply pipe, the weight of the valve 17 will cause the same to automatically open, thus admitting air to the supply pipe and to the spray pipe for the purpose described. Suitable means are also provided for rotating the spray pipe 1 about its longitudinal axis, and, in the present instance, this means 25 comprises a handle 20 connected to the outer end of the spray pipe 1 at a point between the adjustable collar 7 and the stuffing box 9. This handle 20 is preferably secured to the spray pipe 1 by means of a 30 clamp 21 adapted to engage the pipe and to be readily secured thereto in the desired position. The handle 20 is preferably secured to the pipe 1 in a position substantially parallel with the discharge nozzle 4. 35 Thus, the position of the handle 20 on the exterior of the furnace wall will indicate the position of the discharge nozzle 4 relatively to the boiler flues.

The operation of the device will be readily 40 understood from the foregoing description and it will be apparent that, by rotating the spray pipe about its longitudinal axis, the discharge nozzle may be brought into such a 45 position relatively to any of the flues in the boiler as to cause one or more separate and distinct jets of steam to be discharged into that flue; that I have provided this spray pipe with adjustable means for limiting its 50 inward movement to bring the same into the desired position relatively to the ends of the flues; and also that I have provided the device with means for rotating the same, this rotating means being such as to indicate the position of the nozzle. Further, it 55 will be apparent that I have provided means for preventing the discharge nozzle from burning when the same is not in use; that I have provided means for drawing off the 60 waters of condensation from the supply pipe and avoiding the discharge of the same into 65

the flues; that the apparatus as a whole is of a simple and easily operated character and is of a comparatively inexpensive construction, the several parts being, for the most part, of ordinary construction and requiring few parts 70 of special construction; and that, by reason of its construction and its capability of being brought into position to reach all of the flues in the boiler and the manner in which the steam is discharged into the boiler, the device 75 possesses a high degree of efficiency.

I wish it to be understood that I do not desire to be limited to the details of construction shown and described, for obvious 80 modifications will occur to a person skilled in the art.

Having thus fully described my invention, what I claim as new and desire to secure by Letters Patent, is:—

1. In a boiler flue cleaner of the character described, a furnace wall, a boiler mounted within the same, a spray pipe provided with a discharge nozzle extending transversely to said boiler, said spray pipe being rotatably and slidably mounted in said furnace wall, 90 whereby said discharge nozzle may be rotated about an axis extending longitudinally to said boiler and may be moved toward and away from said boiler, a supply pipe extending into the outer end of said spray pipe, and 95 means for controlling the flow of steam through said supply pipe.

2. In a boiler flue cleaner of the character described, a furnace wall, a boiler mounted within the same, bearings mounted in said furnace wall, a spray pipe journaled in said bearings, a discharge nozzle carried by said spray pipe and extending transversely to said boiler and having discharge apertures therein, said spray pipe being slidably mounted in said bearings, whereby the discharge nozzle may be moved transversely to said boiler and may be moved toward and away from the end thereof, a supply pipe extending into the outer end of said spray pipe, and means for controlling the passage of steam through said supply pipe.

3. In a boiler flue cleaner of the character described, the combination, with a furnace wall, and a boiler mounted within the same, of a spray pipe rotatably and slidably mounted in said wall and extending beyond the outer side thereof, a discharge nozzle carried by the inner end of said spray pipe and having apertures adapted to be brought into alinement with the flues of said boiler, a collar adjustably mounted on that portion of said spray pipe extending beyond the outer side of said wall, and a supply pipe extending into the outer end of said spray pipe.

4. In a boiler flue cleaner of the character described, the combination, with a furnace wall, and a boiler mounted within the same, of a spray pipe mounted in said furnace wall and having a discharge nozzle adapted to 130

extend into the flues of said boiler, means for admitting steam to said nozzle, and means for admitting air to said nozzle when the steam has been cut off.

5. In a boiler flue cleaner of the character described, the combination, with a furnace wall, a boiler mounted within the same, a spray pipe journaled in said wall, a discharge nozzle carried thereby and adapted to discharge into the flues of said boiler, and a supply pipe connected to said spray pipe, of means for cutting off the flow of steam through said supply pipe, and automatically operated means for admitting air to said spray pipe when the steam has been cut off from said supply pipe.

6. In a boiler flue cleaner of the character described, the combination, with a furnace wall, a boiler mounted within the same, a spray pipe journaled in said wall, a discharge nozzle carried thereby and adapted to discharge into the flues of said boiler, means for moving said spray pipe toward and away from said boiler, and a steam supply pipe connected to said spray pipe, of means for cutting off the flow of steam through said supply pipe, and automatically operated means for admitting air to said spray pipe when the steam has been cut off from said supply pipe.

7. In a boiler flue cleaner of the character described, the combination, with a furnace wall, a boiler mounted within the same, a spray pipe journaled in said wall and having a discharge nozzle adapted to discharge into the flues of said boiler, means for moving said spray pipe toward and away from said boiler, and a supply pipe connected to said spray pipe, of means for controlling the flow of steam through said supply pipe, a valve mounted in said supply pipe between said controlling means and said spray pipe and adapted to be closed by the passage of steam through said supply pipe and to automatically open when said steam has been cut off from said supply pipe.

8. In a boiler flue cleaner of the character described, the combination, with a furnace wall, and a boiler mounted within the same, of a spray pipe rotatably and slidably mount-

ed in said furnace wall and having its outer end extending beyond said wall, a discharge nozzle carried by the inner end of said spray pipe and adapted to discharge into the flues of said boiler, a stuffing box carried by the outer end of said spray pipe, a supply pipe extending through said stuffing box into said spray pipe, means for controlling the flow of steam through said supply pipe, and means for moving said spray pipe about a longitudinal axis and for moving the same longitudinally.

9. In a boiler flue cleaner of the character described, the combination, with a furnace wall, and a boiler mounted within the same, of a spray pipe rotatably and slidably mounted in said furnace wall, a discharge nozzle carried by the inner end of said spray pipe extending transversely to said boiler and having apertures adapted to be moved into alignment with the flues of said boiler, a supply pipe having its end inserted in the outer end of said spray pipe, a handle for rotating said spray pipe, a valve for controlling the flow of steam through said supply pipe, and means connected to said supply pipe between said valve and said spray pipe for admitting air thereto when said valve has been closed to cut off the steam from said supply pipe.

10. In a boiler flue cleaner of the character described, the combination, with a furnace wall, a boiler mounted within said wall, a spray pipe rotatably mounted in said furnace wall and having a discharge nozzle extending transversely to said boiler, a supply pipe connected to said spray pipe, a cut-off valve inserted in said supply pipe, and a valve-controlled outlet for said supply pipe on that side of said cut-off valve removed from said spray pipe, and an automatic air-admission valve connected to said supply pipe between said cut-off valve and said spray pipe.

In testimony whereof, I affix my signature in presence of two witnesses.

SAMUEL H. LIMBERT.
